UNITED STATES PATENT OFFICE.

JUAN J. FRANCESCHINI, OF NEW YORK, N. Y.

REGISTERING DEVICE FOR PRINTING-PLATES AND THE LIKE.

1,034,606.

Specification of Letters Patent.

Patented Aug. 6, 1912.

Application filed November 2, 1911. Serial No. 658,107.

To all whom it may concern:

Be it known that I, JUAN J. FRANCESCHINI, a citizen of Uruguay, South America, residing in New York city, in the county of New York and State of New York, have invented certain new and useful Improvements in Registering Devices for Printing-Plates and the Like, of which the following is a specification.

10 My present invention relates to an improvement in electrotypes, and more especially pertains to the registration thereof in a press where a plurality of the said electrotypes or halftone plates are used in multi-colored printing processes.

One of the advantages of my device is the precision in which a series or group of plates or blocks may be registered.

Another advantage is the means whereby 20 the plates or electrotypes are caused to take their proper position as relates to the top or bottom of the picture or other design to be printed therefrom.

Another advantage is the means by which 25 these plates may be prepared for mounting by which the successive designs of a group are caused to absolutely register one upon the other in successive printings.

30 A further advantage is that due to the construction of the separate mounting, the electrotypes are easily removed and replaced without taking the mounting from the chase or the chase from the press, and without the taking apart of the holding device.

35 A further advantage is the ease in which the said plates are clamped or unclamped in the chase while said chase is in the press, thereby facilitating their adjustment for printing, or their removal for replacement.

40 In the accompanying drawings Figure 1 is a plan view of a chase, showing a portion of my device locked therein. Fig. 2 is a section of the chase taken on line 1-1, Fig. 45 1 looking in the direction of the arrow. Fig. 3 is a perspective view of my device arranged upon its mounting. Fig. 4 is an enlarged sectional view of Fig. 3 taken on line 4-4, Fig. 3. Fig. 5 is a sectional view taken on line 5-5, Fig. 6, showing a jig for preparing the plates for registration. Fig. 6 is a plan view of the jig. Fig. 7 is a side elevation of the electrotype mounted upon its base block.

55 In Fig. 1 is shown a chase 2 of the usual type used by printers, and having centrally located therein an electrotype base plate 3,

the same being held in the chase by the usual furniture 4 and being clamped therein by means of the usual lock-up members 5, 6, and 7. By referring to Fig. 7 it will be seen that the base block 3 has mounted upon it an electrotype, generally denoted by 8, said electrotype or printing plate being composed of the usual wooden base piece 9 and the electrotype or printing plate 10 fixed thereto. It will further be noted by referring to Figs. 1 and 2 that the base block 3 has arranged thereon a plurality of pins or dowels 11, 12, 13, and 14, and by referring to Figs. 2 and 7, it will further be noted that these dowels project a short distance into the electrotype base 9, thereby holding the electrotype 8 against any lateral movement and at the same time causing said electrotype 8 to be registered.

Where a plurality of the electrotypes 8 are required for the purpose, as previously mentioned, of printing in two or three colors, all of the electrotypes in the group are arranged as above described so that any one 80 of the electrotypes may be quickly removed from the base block 3 and another succeeding electrotype mounted thereon, and without further preparation it will register its portion of the design accurately upon the 85 one previously printed. For this purpose the electrotype base 9 is drilled for the reception of the dowels, the said drilling being done from a pre-determined point arranged on each of the said electrotypes, so that the 90 said plates may be substituted for one another without the removal of the base block 3 from the chase. For accomplishing this, for instance in the case of an electrotype, Fig. 3, wherein is shown the letter W centrally arranged on its base and having arranged at its central lines 4-4 and X-Y and near the outer edges thereof, a plurality 95 of circular forms 15, 16, 17, and 18 are provided. These forms, which have previously 100 been laid out upon the sketch or drawing from which the zinc etching and the electrotype were made, are therefore centrally positioned as regards the design portion of the electrotype 17', which, in this case, is the 105 letter W. The other companion plates of this group, not shown, also have circular forms similar to forms 15, 16, 17, and 18 located thereon in absolutely the same relation to their designs, and it is these said circular forms that are used for the purpose of 110 preparing these blocks for their successive

registrations, and after they have served their purpose they may be routed off.

By referring to Fig. 4, which is an enlarged view taken on line 4—4, Fig. 3, it will be noted that the circular forms 17 and 18 have round depressions 19 and 20 formed therein, which depressions are formed by the natural action of making the original plates in the usual manner. Their use is as follows: The position of the circular forms having been determined on the designs for a series of plates and the plates having been made up and mounted in the usual manner, they are placed in a jig, Fig. 5, which is comprised of a base member 21 and a removable cover member 22. The base member 21 has fixedly mounted therein a plurality of dowels 23, 24, 25, and 26, and these dowels are slidably fitted in holes suitably located in the cover 22 and are used to locate the said cover in accurate position as regards the base portion 21. In said base portion are located a plurality of pins 27, 28, 29, 30, Fig. 5. These pins are fixedly located in the same position as the said predetermined positions for the circular forms 15, 16, 17, and 18, on the electrotype. The ends of these pins are rounded and adapted to fit in the circular depressions in the said circular forms, thereby accurately locating the plates for drilling the registry holes in the mountings. The cover portion 22 has located therein a series of bushings 31, 32, 33, and 34, said bushings being fixed and located to the central lines A—B and C—D, so that when the electrotype 8 is placed face downward on the base member 21, it is located in the jig by means of the depression in the circular forms and the pins 27, 28, 29, and 30. The cover plate 22 is then placed upon the locating dowels in said base plate 21 and the holes are drilled downwardly into the block portion 9 of the electrotype, and the resulting holes are thereby located in said block 9 so as to cause the electrotype, or a series so drilled, when fitted to the dowels 11, 12, 13, and 14, of the base block 3, Fig. 1, to successively and accurately register the said electrotypes in position in the chase for printing.

It is necessary when an electrotype is placed upon the base block 3, that some means be provided for the purpose of clamping and holding the electrotype 8 rigidly when so mounted. In the accompanying drawings I have shown the base block 3 as being provided on opposite sides with a pair of clamping members 35 and 36. The said members 35 and 36 are pivoted in a pair of slots 37 and 38 which are cut in the opposite ends of the said base block 3, and have a pair of upturned edges which are adapted to engage into a pair of oppositely disposed

slots 39 and 40 which are arranged in the ends of the electrotype 8.

As a further provision in the registration of a series of electrotypes, each one of which has a component part of the design thereon, one for each color, and for the purpose of preventing the improper positioning of any one of the said electros in the series, such as, for instance, getting them on the base block 3 upside down, I have arranged that the dowels 11, 12, 13, and 14 on the said base block are not in symmetrical position in relation to one another, but are offset from one another, or other convenient method by which the electrotype may be made irreversible in its mounting, thereby preventing the same from being turned end for end. It is obvious that with this arrangement of the said dowels in the base block that the holes in the mounting of the electrotypes must bear the same relative positions.

Having thus described my invention, I claim:

1. In a registering device for printing plates of the class described, comprised of an electrotype or halftone block, said block having a plurality of holes irregularly arranged thereon, a mounting therefor, said mounting having a plurality of dowels adapted to fit in said holes, whereby said electro or halftone block may be limited to one relative position on said mounting, thereby preventing the improper setting of the plate.

2. In a registering means for printing plates of the class described, comprised of an electrotype or halftone block, said block having a plurality of holes unsymmetrically arranged thereon, a mounting therefor, said mounting having a plurality of dowels adapted to fit in said holes, whereby said electro or halftone block may be limited to one relative position on said mounting, thereby preventing the improper setting of the plate, clamping means carried by said mounting and means on said electrotype or halftone mounting adapted to be engaged by said clamping means.

3. In a registerable printing plate of the class described, comprised of a detachable electro or halftone block and a base-block therefor adapted to be held in the chase of a printing press, dowels in said base-block and holes in said electro or halftone block, said holes being adapted to fit said dowels, and locating points carried on the printing face of said electro or halftone block for the purpose of locating the same to permit of the drilling of said registering holes.

JUAN J. FRANCESCHINI.
